UNITED STATES PATENT OFFICE.

HERMAN JOHN PIEPGAS, OF CALDWELL, IDAHO.

SAFETY ATTACHMENT FOR ELEVATORS.

1,081,771.

Specification of Letters Patent. Patented Dec. 16, 1913.

Application filed July 24, 1912. Serial No. 711,247.

To all whom it may concern:

Be it known that I, HERMAN J. PIEPGAS, a citizen of the United States, and a resident of Caldwell, in the county of Canyon 5 and State of Idaho, have invented a new and Improved Safety Attachment for Elevators, of which the following is a full, clear, and exact description.

My invention relates to elevators, and it 10 comprises a safety attachment for automatically stopping the elevator in case the load is not removed therefrom before the elevator platform reaches the highest point of its travel, and thus avoiding injury to the persons or things on the platform and damage 15 to the parts of the elevator itself.

My invention is especially designed to be used in connection with elevators of the endless belt or conveyer type, and it is so 20 constructed that the parts which actuate the safety attachment to stop the elevator are forced into operative position by the weight of the person or other thing which the elevator carries, so that in case the load is not 25 removed before the platform on which the same is carried reaches the turning point at the top, the elevator is stopped by the engagement of certain parts which serve to disconnect the elevator from the source of 30 the driving power.

Reference is to be had to the accompanying drawings forming a part of this specification, in which the same characters of reference indicate the same parts in both the 35 views.

Figure 1 shows a side elevation of my safety attachment in position upon an elevator of the kind mentioned; and Fig. 2 is a front view of the same.

40 The numeral 1 indicates a pair of standards or upright bearings in which is carried a shaft 2, over which passes an elevator belt or conveyer 3. This belt is of a type commonly used in buildings having several 45 floors, and in practice it will run from the basement to the top floor and may be used for lifting either persons or freight to the required height. On the top floor are arranged standards for upright bearings 4 carrying a driving shaft 5, whereon is 50 mounted a pulley serving as an operating pulley and driven by any suitable source of power. The numerals 6 represent guards on either side of the belt or conveyer 3, which 55 are perforated to allow of the passage of the

shafts 2 and 5, and which extend from the bottom of the elevator to the top, as shown.

One of the standards 4 at the top of the elevator, preferably the one shown at the right in Fig. 2, is hollow and contains actuating gearing for turning the shaft 5. This gearing is not shown, but it may be of any suitable type and be driven from a shaft 7 which enters the bearing and is supported at its outer end by any suitable standard. This shaft has mounted on its projecting portion a loose pulley 8 and a fixed pulley 9, and over the fixed pulley is passed an operating belt 10, by means of which driving power is supplied. 70

The belt 3 is provided with a number of steps or platforms, each of which comprises a board or plate 11 fixed to triangular frames 12 at each end. These triangular frames 12 have shanks 13 extending therefrom, these shanks being pivotally secured to the belt so as to permit the plate or platform 11 to be rotated through substantially 90°. The plate 11 is rigid with the frames 12, and these frames also have rigidly secured thereto a plate 14 which extends substantially at right-angles to the plate 11, and has projections 15 at its ends which engage the guards 6 to hold the plate 11 in horizontal position while the platform is 80 moving in an upward direction. At this time the projections 15 will simply slide upon the edges of the guards in a manner that will be readily understood. 85

The plate 11 has four apertures passing therethrough near the corners, and these apertures receive headed bolts 16 which are rigidly secured to the top of the platform shown at 17. This top 17 is held spaced from the plate 11 by means of spiral springs, and it has rigidly secured centrally thereto and projecting downward a rack 18, a central aperture being provided in the board 11 to give passage to this rack. So long as the top 17 is not weighted the springs associated with the bolts 16 will force the top upward as far as the bolts permit, but when the top is weighted the springs will yield so as to move the rack bar 18 downward. 90 A fifth spring may be used surrounding the 100 rack bar between the board 11 and the top 17, as shown. 105

The lower end of the rack bar 18 projects through a bearing 19 carried by the plate 14, and this rack bar is provided with rack 110

teeth along a section of its length to engage with a pinion 20 mounted upon a shaft 21 carried by bearings 22 rigidly supported upon the lower face of the plate 11. This 5 shaft 21 has a second gear 23 which meshes with a horizontally movable rack bar 24 which slides in bearings 25 also carried upon the lower face of the board 11. The rack bar 24 is movable transversely with respect 10 to the direction of travel of the belt for a purpose which will appear later.

26 is an endless cord which passes over pulleys 27 mounted upon one of the guards 6 near the lower end thereof, and pulleys 15 28 carried by the standards 29 adjacent the hollow top bearing 4. Other guide pulleys 30 are employed, and below these last-named pulleys is a triangular frame 31, this frame being shaped approximately like the figure 20 four and having eyelets to which the ends of the cords 26 are secured. The apex of this frame points upward, and the base of the triangle forms a shoulder adapted to be engaged by the rack 24 when the latter projects far enough.

25 The belt 10 is engaged by a belt shifter which comprises a shank 32 and a yoke 33, this yoke having eyelets carried by either arm thereof, to which the cord 26 is secured. 30 Any movement of the cord will move the belt off of the pulley 9, and the parts are arranged so that the belt 10 when moved off the operating pulley will be moved upon the loose pulley 8.

35 The manner of operation of my invention is as follows: When either platform is on the side of the belt which is traveling upward it will automatically turn about the pivoted ends of the parts 13 until it comes into the 40 lowest possible position, with the projections 15 resting upon the lateral edges of the guard 6, and the top 17, as well as the board 11, in horizontal position. So long as this platform is not weighted the top 17 will be 45 held up by the springs, and the rack 24 will occupy the position shown in Fig. 2, but should a weight be placed upon the top 17, this top will sink, moving the rack 18 down and turning the shaft 21 so as to cause the 50 rack 24 to be moved outward. With the parts in this position the weighted platform will be carried upward, and the person or other object on the platform can be lifted as high as necessary; and if the platform is 55 cleared before the top floor is reached the top 17 will be again forced up to withdraw the bar 24 and allow the elevator to continue in motion. If, however, through oversight or for some other reason the platform re- 60 mains weighted before the top floor is reached, the bar 24 will remain in projecting position and engage the shoulder of the frame 31 as soon as it reaches it. This will cause the cord 26 to shift, and through 65 the belt shifter the operating belt will be

moved over on the loose pulley 8 and thus stop the elevator. In this way accidents can be avoided, as otherwise the load upon the platform would be carried over the operating pulley carried by the shaft 5 at the 70 top, and as soon as this happens the platform will automatically move, because of its own weight, from the position shown near the middle of Fig. 1 at the left to the position shown near the top of Fig. 1 at the 75 right, and anything on the platform when it moves in this way will be thrown off. The result might be serious injury and damage, but the danger of such injury and damage is entirely obviated by the rack 24 en- 80 gaging the frame 31 to shift the operating belt over upon the loose pulley and thus stop the elevator and give notice that the load on the uppermost platform must be removed before the elevator can again be 85 safely set into motion.

From the above description it will be seen that I have provided a very efficient attachment for the purpose in view, and that by its use an elevator of the kind described can be 90 automatically stopped under the conditions described and accidents entirely avoided.

I wish to have it understood that the above description is illustrative only, and that I do not care to be limited to the exact 95 details herein set forth, but reserve to myself the right to make such changes in the shape, size and arrangement of the parts as fairly fall within the scope and spirit of my invention.

Having thus described my invention, I 100 claim as new and desire to secure by Letters Patent:

1. The combination in an elevator, of belt gearing for driving the same, a belt shifter, 105 an endless cord connected to the belt shifter and extending parallel with the direction of travel of the elevator platform, a frame having a shoulder carried by said cord, and a movable member carried by the elevator 110 platform and adapted to be moved into position to engage the shoulder to operate the cord and move the belt out of operative position in case the elevator platform remains loaded when it nears the upper end of its 115 travel.

2. The combination in an elevator, of a platform having a movable top carried by said elevator, a transversely-movable member carried by the platform, means engaging 120 said member and movable by the platform top when the same is depressed to project said member beyond said platform, and means for disconnecting the elevator from the driving power actuated by said member 125 in case the platform remains loaded when the same reaches the upper end of its travel.

3. The combination in an elevator, of a platform having a depressible top, a rack bar movable to project beyond the side of 130

the platform, a rack bar secured to the top, gearing engaging said rack bars to move the first-named rack bar into projecting position when the platform top is depressed, 5 and a belt shifter operated by the projecting rack bar to stop the elevator in case the platform remains loaded when the same approaches the upper end of its travel.

4. The combination of an elevator platform, resilient means for supporting said platform, a projection movably mounted on said platform, means operable by the load on said platform for moving said projection into projecting position, a belt shifter, 15 and means for operating the same, said means being actuated by said projection.

5. The combination of an elevator platform comprising a movable top, a movable member mounted upon said platform, a connection 20 between said movable top and said member to cause said member to project when the top is depressed, a belt shifting device, and means for operating the same, said means being engageable by the said member to be actuated.

6. The combination of an elevator platform having a depressible top, resilient means for supporting said top, a rack bar slidably carried by said platform, a gear

wheel engaging said rack bar, a spindle on 30 which said gear wheel is mounted, a second gear wheel on said spindle, a rack bar carried by the top and engaging the second gear wheel to project the first rack bar when the top is depressed, a belt shifter, and 35 means for operating the same to be engaged by the first rack bar when the same has been moved to projecting position.

7. The combination of a flexible member, 40 a triangular frame interposed in said flexible member, and having one side in line therewith and its other two sides extending therefrom, guide pulleys for the said flexible member, a belt shifting device to the opposite sides of which the ends of the said flexible member are connected, and an elevator platform having means for engaging said triangular frame to move the flexible member to actuate the said belt shifting device 45 to stop the elevator. 50

In testimony whereof I have signed my name to this specification in the presence of two subscribing witnesses.

HERMAN JOHN PIEPGRAS.
